CLAIM

The ornamental design for a lighting fixture, as shown and described.

DESCRIPTION

FIG. 1 is a front perspective view of a new lighting fixture; FIG. 2 is a back perspective view thereof; FIG. 3 is a front elevational view thereof; FIG. 4 is a left elevational view thereof; FIG. 5 is a right elevational view thereof; FIG. 6 is a top plan view thereof; FIG. 7 is a bottom plan view thereof; and, FIG. 8 is a back elevational view thereof.

The broken line disclosure in the views represents portions of the lighting fixture that form no part of the claimed design. The broken-line extending out beyond the perimeter of the back surface of the fixture in FIGS. 4-7 is intended to demonstrate environment only and forms no part of the claimed design.
